PILE CUTTING SAW

Filed Sept. 22, 1922.

2 Sheets-Sheet 2

UNITED STATES PATENT OFFICE.

JOHN P. BALL, OF CHICAGO, ILLINOIS.

PILE-CUTTING SAW.

Application filed September 22, 1922. Serial No. 589,903.

To all whom it may concern:

Be it known that I, JOHN P. BALL, a citizen of the United States, residing in the city of Chicago, county of Cook, and State of Illinois, United States of America, have invented a certain new and useful Improvement in Pile-Cutting Saws, of which the following is a specification.

This invention relates to a device more especially adapted for sawing off pile timbers under water, by utilizing a straight blade saw connected with a twin driving engine, and aims to provide certain improvements therein.

Heretofore it has been common to pump out the water by building coffer dams surrounding the structure, and also by using circular saws driven above the water surface.

My invention provides improvements especially applicable to devices of this general character, and in its preferred form it utilizes a straight blade saw driven by a twin engine, preferably operated by compressed air; a plurality of traction rollers driven by suitable means operated by the twin motor; a frame for supporting all of the parts; means for supplying and controlling the compressed air for the motor; and means for guiding the direction of the device by hand;

My invention also includes bracing arms carrying the twin engines and suitable frame members supporting the main arms, guide means for holding the machine in position while the saw is in operation; pulleys or wheels secured to the journals of the traction rollers in conjunction with belts whereby all the traction wheels are operatively connected together and various improvements in construction, arrangement and design, all of which will be hereinafter more fully set forth.

In the accompanying drawings, which show a certain adaptation of my invention and form a part of my specification, Figure 1 is a plan of my invention. Figure 2 is a side elevation. Figure 3 is a sectional elevation taken substantially on the line 3—3 of Figure 1, looking in the direction of the arrows.

Referring to the drawings A indicates two bracing arms; B, the twin engines; C is a blade saw; D the forward driving mechanism; E the traction elements or rollers; F flexible guide rods; G rods connected with the pistons of the engine for actuating

means whereby the traction rollers are operated.

The various elements thus generally referred to may be of any suitable construction and arrangement capable of supporting and operating the saw and for guiding and driving the device forward.

Referring to the figures, I will now describe in detail the preferred form of my invention illustrated.

The bracing arms A preferably consist of four longitudinal channel irons *a* and a sufficient number of diagonal bracings *b*, the bracing arms on opposite sides of the device being connected by transverse bars *c*, which also support the traction rollers E. Attached to the bracing arms on opposite sides of the device are two guiding handles, *d*, which are preferably braced by two upright rods, *e*.

The twin engines generally indicated at B consist of two cylinders *f*, each provided with a piston *g*, (shown in dotted lines in Figure 1) and two D valves *h*. These are supported and bolted to the bracing arches by the bent ends *i*. The driving power is preferably compressed air and is supplied by the intake pipe *j*, and the exhaust pipe *k*. The saw blade C is preferably a stiff blade with suitable teeth *l*, and is bolted to the pistons at *m*.

The forward driving mechanism is a slow geared ratchet wheel having angular teeth *n* into which a pawl *o* drops; the pawl *o* being pivotally secured to the arm *o*, which in turn is pivotally connected to link *o*. On the lower side of this ratchet wheel is a beveled gear which drives a corresponding bevel wheel *p*, which is bolted to a driving shaft *q*. On this driving shaft *q*, at either end, is a pulley *r*, and a belt or chain *s*, which drives the pulleys at the end of the shafts of the traction rollers, shown at *t*. The traction rollers *t* are preferably sharp toothed wheels which catch in the surface or top of the pile and induce a forward travel of the frame and the saw; the sharp toothed wheels being firmly secured to the driving shafts.

The flexible guide rods F are intended to straddle the pile being cut and serve to hold the frame in suitable position so that the saw may operate; the forward ends of the rods F being preferably bowed outwardly so as to compensate for varying thicknesses of piles and thus ensuring a straddling of the piles as the device is being fed forward.

The guide rods are preferably made up of the bars *u*, attached to the frame at the rear end of the bracing arms and are further supported by the spring rods *v*, fastened 5 to the bracing arms at *w*. The driving rods *G* for actuating the pawl and ratchet mechanism of the traction mechanism, are connected at the forward ends with the pistons of the cylinders *f* by a pin and slot as at *m* 10 and fulcrumed intermediate of their ends at *x*. The link *o* is pivoted to the cross arm *y*, which is pivotally connected to both driving rods *G*; and the rear ends of the driving rods are held in proper position by 15 means of a brace plate *z*.

H indicates the piles which have been sawed or cut off; while *I* indicates a pile partly cut off.

It will be understood that the device is 20 intended to operate under water but not limited thereto and can be employed to cut foundation piling, sheet piling or construction timbers.

What I claim is:—

- 23 1. A pile cutting saw, comprising a frame adapted to be disposed across the piling, power-imparting means mounted on said frame and provided with a reciprocating piston, a saw-blade secured to the piston so as to reciprocate therewith, guiding members for controlling said frame, and means mounted intermediate of the sides of the frame and operatively connected with the piston whereby the frame is fed forward 25 while the saw-blade is operated.
- 25 2. A pile cutting saw, comprising a frame, a longitudinally disposed saw-blade, power-imparting means whereby the saw-blade may be reciprocated, traction mechanism 40 adapted to engage with and travel on the sawed upper ends of the piles, and means intermediate of the saw-blade and the traction mechanism whereby the device is moved forward as the saw-blade reciprocates.
- 45 3. A pile cutting saw, comprising a frame adapted to extend transversely of the piling, a pair of motors mounted at the forward end of the frame and on opposite sides so as to have their pistons reciprocate 50 horizontally, means for controlling the power medium for said motors, a saw-blade

connected at its opposite ends to the pistons of both motors, traction rollers mounted between the sides of the frame, adapted to engage with the tops of the sawed piles, means for driving the traction rollers, and means intermediate of the roller driving means and the motor-pistons whereby the saw is advanced with each complete reciprocation of the saw-blade. 55

4. A pile cutting saw, comprising a main frame, traction rollers mounted on said frame so as to travel on the tops of the sawed piles, power-imparting means mounted on said frame, a saw-blade connected with said power imparting means so as to be reciprocated thereby, yielding members secured to the frame so as to extend in advance of the saw blade, said members being adapted to straddle the pile being sawed, to 70 guide the frame, and means intermediate of the power-imparting means and the traction rollers whereby the frame is advanced with each complete reciprocation of the saw-blade. 75

5. In a pile cutting saw having a main frame provided with a horizontally disposed saw and power imparting means for driving the saw, traction rollers secured beneath the frame so as to travel on top of the sawed piles, driving mechanism for said rollers, pawl and ratchet mechanism for intermittently actuating said driving mechanism, and means intermediate of the power imparting means and said pawl and ratchet 85 mechanism for imparting movement to the latter. 85

6. In a pile cutting saw and similar devices the combination with a plurality of traction rollers adapted to travel on the sawed ends of the timbers, and a blade saw fed to the uncut timber by said traction rollers, of flexible guide rods in contact with said timbers, levers connecting the saw blade with the feeding mechanism to drive the 90 saw, and hand holders for guiding and freeing the frame. 95
